UNITED STATES PATENT OFFICE.

GUSTAVUS A. BAUER, OF CHICAGO, ILLINOIS, ASSIGNOR TO HUGRO MANUFACTURING COMPANY, OF WARSZAWA, POLAND, A CORPORATION OF INDIANA.

BRUSH CONSTRUCTION.

1,407,913.

Specification of Letters Patent. Patented Feb. 28, 1922.

Application filed March 10, 1921. Serial No. 451,175.

To all whom it may concern:

Be it known that I, GUSTAVUS A. BAUER, a citizen of the United States of America, and resident of Chicago, Cook County, Illinois, have invented a certain new and useful Improvement in Brush Construction, of which the following is a specification.

My invention relates to an improvement in brush construction, and more specifically to an improved and efficient means for securing a tuft of bristles within a recess in the brush spindle.

My invention is particularly adapted for use in connection with brushes in which the spindle is made of metal or other hard material, and by my invention the attaching means for the tufts of bristles do not project on to the surface of the spindle, so that the spindle is provided with a clear plane surface between the various tufts of bristles, so that lint or other material will not collect upon the spindle when the brush is being used.

The features and objects of my invention will be more readily understood by having reference to the accompanying drawings, in which I have illustrated my invention in connection with a brush of the type particularly adapted for use in carpet cleaners.

Figure 1 is a side elevation of a section of a brush embodying the features of my invention, one of the tufts of bristles being removed.

Fig. 2 is a transverse sectional view.

Fig. 3 is a longitudinal sectional view of a portion of the brush.

As illustrated, the brush consists of a cylindrical spindle 4, which is preferably made of metal, within which is secured a series of tufts of bristles 5. Each of these tufts of bristles are inserted within a cylindrical recess 6 in the spindle 4, and are held within this recess by an attaching wire 7. These tufts of bristles are formed by folding the bristles at their center and the wire 7 is formed with a hook at one end which passes around the bristles. This attaching wire is provided with an elongated shank 8 which, when the tufted bristles and attaching wire

are inserted within the recess 6, projects through the opening 9 which is bored through the spindle 4 to the opposite side

thereof. The end of the shank 8 is riveted or otherwise secured to the spindle, as indicated at 10. This attaching wire, however, is formed flush with the surface of the spindle so that the spindle presents a substantially uninterrupted and smooth surface between the various tufts of bristles. The end 11 of the hook portion of the attaching wire 7 rests against the bottom of the cylindrical recess 6. When the attaching wire is thus riveted in position, it operates to firmly and securely hold the tufts of bristles in position. When a pulling strain is exerted on the bristles, it will tend to straighten the hook portion of the attaching wire and the end 11 will be forced against the side of the recess 6. This engagement will prevent the straightening of this hook portion, and thus prevent the bristles from being pulled out of the recess in the spindle.

It will thus be seen that I have devised a very simple and efficient attaching means for the tufts of bristles which is particularly adapted for use in connection with metallic spindles or spindles made of some other material which is of such hardness that the ordinary staple cannot be driven into the same. Furthermore, by reason of the free uninterrupted surface of the brush spindle, my invention produces a brush which is very efficient for use in connection with carpet cleaning machines, as no dust or lint will catch on the brush spindle.

What I claim as my invention is:

1. In a brush construction, a spindle having a recess therein, a folded tuft of bristles inserted within said recess, an attaching wire for securing said bristles within said recess, said attaching wire being provided with a hooked end portion passing around said bristles, one end of said hook engaging against the bottom of said recess and adjacent the side wall thereof, the other end of said wire passing through an opening formed in the bottom of said recess to the opposite side of said spindle, and secured to the spindle, the end of said wire being substantially flush with the surface of said spindle.

2. In a brush construction, a spindle having a recess in one face thereof, a hole extending from the bottom of said recess to

the opposite surface of said spindle, a tuft
of folded bristles inserted within said recess,
an attaching member for securing said tuft
within said recess, said member being pro-
5 vided with a hooked end portion passing
around said bristles, the end of said hook
engaging against the bottom of said recess,

the other end of said attaching member
passing through said opening and being se-
cured to the opposite surface of said
spindle.

Signed by me at Warsaw, Ind., this 1 day
of March, 1921.

GUSTAVUS A. BAUER.
